Primary Examiner—T. Chase Nelson*Assistant Examiner*—John Windmuller(74) *Attorney, Agent, or Firm*—Weingarten, Schurgin, Gagnebin & Lebovici LLP(57) **CLAIM**

The ornamental design for a wireless remote control device, as shown.

DESCRIPTION

FIG. 1 is a perspective view of the wireless remote control device.

FIG. 2 is a front view of the wireless remote control device; FIG. 3 is a right side view of the wireless remote control device;

FIG. 4 is a left side view of the wireless remote control device; FIG. 5 is a bottom view of the wireless remote control device; FIG. 6 is top view of the wireless remote control device; and, FIG. 7 is a back view of the wireless remote control device. The “R” symbol at the bottom of FIGS. 1 and 2 is a registered trademark of Russound.

The broken lines in the figures depict portions of the remote control device that form no part of the claimed design.
